[57] **CLAIM**

The ornamental design for a roadway vehicle tire spike, as shown and described.

DESCRIPTION

FIG. 1 is a top plan view of the roadway vehicle tire spike showing my new design;

FIG. 2 is a end elevation view of the invention thereof;

FIG. 3 is a alternate end elevation view thereof;

FIG. 4 is a side view with the device folded thereof;

FIG. 5 is a cross-sectional view along line 5—5 of FIG. 4;

FIG. 6 is a side elevation view thereof;

FIG. 7 is an alternate side elevation view thereof; and,

FIG. 8 is a bottom plan view of the invention showing my new design.
